(57) **CLAIM**

The ornamental design for a storage bin rack, as shown and described.

DESCRIPTION

FIG. 1 is a perspective view of a storage bin rack showing my new design holding a plurality of storage bins shown in phantom.

FIG. 2 is a front elevational view thereof, the opposite rear side being a mirror image thereof.

FIG. 3 is a side elevational view thereof, the opposite rear side being a mirror image thereof.

FIG. 4 is a top plan view thereof.

FIG. 5 is a bottom plan view thereof.

FIG. 6 is a perspective view of another embodiment of a storage bin rack showing my new design holding a plurality of storage bins shown in phantom.

FIG. 7 is a front elevational view thereof, the opposite rear side being a mirror image thereof.

FIG. 8 is a side elevational view thereof, the opposite side being a mirror image thereof.

FIG. 9 is a top plan view thereof; and,

FIG. 10 is a bottom plan view thereof.

The broken lines showing in FIGS. 1 and 6 are for purposes of illustrating environment only and form no part of the claimed design.
